(57) **CLAIM**

We claim the ornamental design for an electronic device case, as shown and described.

DESCRIPTION

FIG. 1 is a front perspective view of an electronic device case; FIG. 2 is a bottom plan view of the electronic device case; FIG. 3 is a top plan view thereof; FIG. 4 is a back elevational view thereof; FIG. 5 is a front elevational view thereof; FIG. 6 is a left elevational view thereof; and, FIG. 7 is a right elevational view thereof.

The broken lines shown on or along the perimeter of the device cover represent stitching and are part of the claim. The short, randomly placed undulating lines depicted in the figures are for illustrating a texture of the device cover and form part of the claim.
